UNITED STATES PATENT OFFICE.

JAMES POLK RAWLS, OF COLUMBIA, SOUTH CAROLINA.

BELLOWS-ACTUATING MECHANISM FOR MUSICAL INSTRUMENTS.

1,083,136.

Specification of Letters Patent.

Patented Dec. 30, 1913.

Application filed July 25, 1912. Serial No. 711,422.

To all whom it may concern:

Be it known that I, JAMES POLK RAWLS, a citizen of the United States, and a resident of Columbia, in the county of Richland and State of South Carolina, have invented a new and useful Improvement in Bellows-Actuating Mechanism for Musical Instruments, of which the following is a specification.

10 My present invention relates to means for operating musical instruments, such as organs, player pianos and the like which include power bellows and is in the nature of a player's bench and certain novel connections with the instrument whereby the instrument bellows may be actuated by a minimum effort on the part of the player.

An object of my invention is to provide a simple, though highly efficient construction adapted to support the player of the instrument and to be actuated by a simple body movement of the player without necessitating pedaling of the feet, as is usual.

25 A further object of my invention is to provide connections extending into the musical instrument and having connection with the bellows, which are of such a nature that the case of the musical instrument need not be open, but on the contrary, may be uniformly maintained in a mouse-proof condition.

30 Other objects, and advantages of my invention, will be apparent from the following description, in which reference is made to the accompanying drawing forming a part of this specification, and in which,

35 Figure 1 is a partial vertical section through a musical instrument and my improvements shown in connection therewith; Fig. 2 is a vertical section taken through my improved player's bench substantially on the line 2-2 of Fig. 1; Fig. 3 is a horizontal view through the same taken substantially on the line 3-3 of Fig. 1; and Fig. 45 4 is a detail perspective view of certain parts to be hereinafter specifically referred to.

40 In accordance with my invention, a musical instrument, such for instance, as a player piano indicated at A and which is adapted to be automatically actuated by mechanism including bellows a mounted in the lower portion of its case, may be formed with an integral unbroken lower case front a', inasmuch as I propose to journal a vertical post B through the base a' of the piano case, the upper portion b of which post is within the

instrument case as clearly shown in Fig. 4. This upper portion b of the post is squared and provided with oppositely extending side members b' having connection with the bellows blocks a² whereby when the post B is oscillated these bellows blocks will be simultaneously moved in opposite directions whereby to alternately exhaust and inflate the bellows a. As shown particularly in Figs. 1 and 3, the lower exterior portion of the oscillatory post B is provided with an angular arm or crank b², to which one end of an outwardly extending connecting rod C has a permanent pivotal connection at c.

50 My improved player's bench comprises a seat D, and a lower seat supporting frame D', of which the former is provided with ribs d extending along its under surface, certain of which ribs, as particularly shown in Fig. 1, are recessed at opposite ends in order to receive the upper cross bars e of U-shaped pivot bars E, the lower extremities of which are bent outwardly at an angle and adapted for engagement within slots 75 d' of the supporting frame D'. Certain other of the seat ribs d are adapted to receive between them the upper end of a vertical lever F, the upper end of which is pivotally connected to the seat by a pivot f 80 extending through the said ribs between which its upper end is disposed as shown in Fig. 2. Intermediate its upper and lower ends the lever F is provided with a longitudinal slot f', through which slot extends 85 a transverse bar G, forming the fulcrum of the lever F and supported through portions of the seat frame D'. The lower end of the lever F is pivoted, by means of a readily removable pin H to the forked outer 90 end c' of the connecting rod C. Thus with the seat frame disposed in relation to the musical instrument, as shown in Fig. 1, and with the connecting rod C coupled to the lever F by pin H, the player may, by forward and rear body movements, rock the lever C and thus oscillate the post B through the connections named.

95 It is to be understood that the body movements necessary for the accomplishment of the functions stated are very slight, being in practice hardly perceptible owing to the fact that the particular post B and its connections with the bellows blocks a² may be so regulated as to produce relatively greater movement at the ends of the rod b' than is communicated to the swinging seat D. It

should be further noted that it is simply necessary to place the seat and its frame in proper relation to the musical instrument and couple the connecting rod C to the seat lever F by means of pin H, preparatory to playing, and that when it is desired to discontinue the playing, the pin H may be removed, thus freeing the connecting rod C whereby the latter may be swung on its pivot c to a position beneath the piano and concealed from view.

A further and important feature of my invention lies in the particular connection with the instrument bellows, inasmuch as by mounting a single post B through a journal in the base a^2 of the instrument, the latter may be maintained in a mouse-proof condition irrespective of whether it is in use or not.

I claim:—

1. A player's bench for musical instruments, embodying a supporting frame, a seat pivotally supported on said frame and

movable horizontally by body movements of the player, and an upright member intermediately pivoted in the frame having a pivotal connection at its upper end with said seat.

2. A player's bench for musical instruments embodying a supporting frame, a seat having recessed ribs upon its lower surface, U-shaped members having lower offset ends journaled in portions of the supporting frame and having their upper cross bars disposed within the recesses of said seat ribs whereby to enable playing movement of the seat with respect to the supporting frame, and a lever having an intermediate pivot in the supporting frame and having connection at one end with the said seat, substantially as described.
